[57] **CLAIM**

The ornamental design for a housing panel for a portable cellular radio telephone or similar article, as shown and described.

DESCRIPTION

FIG. 1 is a front, top and right side perspective view of a housing panel for a portable cellular radio telephone or similar article showing our new design;

FIG. 2 is a rear elevational view thereof;

FIG. 3 is a left side elevational view thereof.

The broken line showing of a casing outline and antenna is for illustrative purposes only and forms no part of the claimed design.

FIG. 1

FIG. 2

FIG. 3
